WRINGER

George W. Dunham, Westport, Conn., assignor
to General Electric Company, a corporation of
New York

Application May 17, 1941, Serial No. 393,983

9 Claims. (Cl. 68—253)

The present invention relates to wringers for use with domestic washing machines.

The object of my invention is to provide an improved construction for driving and controlling wringers of this type, and for a consideration of what I believe novel and my invention, attention is directed to the following description and the claims appended thereto.

In the accompanying drawings, Fig. 1 is a front elevation, partly broken away, of a wringer embodying my invention; Fig. 2 is a sectional elevation of the pressure adjustment; Fig. 3 is a sectional top elevation of the wringer; Fig. 4 is a front view of the wringer; Fig. 5 is an exploded perspective view of the control mechanism; Fig. 6 is a fragmentary view showing the latch holding the driving mechanism in one of the operative positions; Fig. 7 is a similar view showing the latch holding the driving mechanism in the other operative position; Fig. 8 is a front elevation, partly broken away, of a modification; Fig. 9 is a sectional view taken on line 9—9 of Fig. 8; Fig. 10 is a top plan view of the control handle; Fig. 11 is a fragmentary view showing the wringer driving mechanism latched in one of its operative positions; Fig. 12 is a view similar to Fig. 11 showing the wringer driving mechanism latched in the other of its operative positions; and Fig. 13 is a front view of the wringer.

Referring to the drawings there is shown a wringer having a frame comprising side stiles 1 and 2 fixed at their lower ends to a bottom frame member 3. Drainboards 3b are fixed to the side stiles by ears fitting in slots 3c. Between the side stiles are upper and lower wringer rolls 4 and 5 having shafts 6 and 7 journaled in bearing blocks 8 and 9. The bearing blocks 9 are seated at the lower ends of the side stiles. The bearing blocks 8 are slidably carried in the upper ends of the side stiles and are urged toward the lower bearing blocks to press the rolls together by a leaf spring 10 carried on the lower end of an adjusting screw 11 threaded in a nut 12 fixed at the center of a top frame member 13. One end of the top frame member 13 is pivoted on a bracket 15 carried by a wringer head 16 fixed to the side stile 1. The other end of the top frame member 13 is releasably connected to the side stile 2 by a toggle comprising links 17 pivoted at 17a on the upper end of the side stile 2 and a link 18 pivoted at 19 on the top frame member 13, and pivoted at 20 to the lower ends of the links 17. When the links 17 and 18 of the toggle are in

the pressure applying position, the pivot pins 20 are slightly to the right of a center line connecting the pivot pins 17a and 19. The upward force exerted on the pivot 19 by the roll pressure accordingly tends to pivot the links 17 and 18 so as to bring the pivots 20 still further to the right. In other words, when the toggle formed by the links 17 and 18 is in the pressure applying position, it is slightly short of its dead center position.

The toggle is held in the pressure applying position by a latch 21 pivoted at 22 on the side stile 2 and having a hook 23 at one end engaging one of the pivot pins 20. The other end of the latch 21 is pivotally connected at 24 to an operating link 25. Upon moving the operating link 25 to the right, as viewed in Fig. 1, the hook 23 of the latch 21 is moved clear of the pin 20 to release the toggle and permit upward movement of the righthand end of the top frame member 13 and thereby release the pressure between the rolls. The operating link 25 is biased to the latching position by a tension spring 26 arranged between the left-hand end of the operating link and a stud 27 on the wringer head 16. The spring 26 tends to hold the latch 21 in the position shown in Fig. 1. After tripping of the latch 21 to release the pressure between the rolls, the pressure can be reapplied by manually moving the toggle link 18 to the position shown in Fig. 1, and upon reaching this position the toggle link will be latched in place by the latch 21. The latch 21 and its associated parts provide an arrangement for quickly releasing the roll pressure in emergencies.

The lower roll shaft 7 is connected by a coupling sleeve 28 to a crown gear 29 journaled in a bearing 30 in the wringer head 16. The crown gear is selectively driven in opposite directions by pinions 31 loose on a vertical shaft 32 journaled at its upper end in a bearing 33 in the top wall of the wringer head and having a coupling member 34 at its lower end guided in a tubular post 35 by means of which the wringer head is rotatably supported on the upper end of the wringer post of a domestic washing machine. At the lower end of the post 35 is a flange 36 which is adapted to rest on a similar flange fixed to the wringer post. The flange 36 carries a spring pressed detent 37 which is adapted to fit into holes in the wringer post flange and hold the wringer in fixed angular position with reference to the wringer post. Upon lifting the detent 37 by means of a lever 38 the wringer can be swung

about the wringer post to the desired position. The coupling member 34 is provided with a slot 39 by means of which the shaft 32 is driven by a drive shaft extending upward through the wringer post.

The direction of rotation of the crown gear 29, and therefore the direction of rotation of the wringer rolls, is controlled by coupling one or the other of the gears 31 to the shaft 32. This is effected by means of a shifting member 40 having yokes 41 received in grooves 42 in the gears 31. The shifting member 40 is fixed to a slide 43 which is biased to the neutral position illustrated, by a compression spring 44 confined between shoulders 45 on the wringer head. The ends of the compression spring 44 cooperate with ears 46 on the slide to return the slide to the neutral position. In the neutral position clutch teeth 47 on the gears 31 are clear of driving pins 48 on the shaft 32. By moving the slide 43 up or down from the neutral position the clutch teeth on the lower or the upper gear 31 respectively are moved into engagement with the driving pins 48 to complete a driving connection to the wringer rolls. Both of the gears 31 are constantly in mesh with the crown gear 29 but only one of the gears can be in the driving position.

The wringer is controlled by handles 49 fixed to opposite ends of a shaft 50 slidably and rotatably carried in bosses 51, 52 on the wringer head. The ends of the shaft 50 project through opposite sides of a shield 50a enclosing the wringer head. The sliding movement of the shaft 50 is limited by a pin 53, fixed in the shaft, which cooperates with the boss 51 and by a collar 54, fixed on the shaft, which cooperates with the boss 52. The slide 43, which controls the rotation of the wringer, is connected to one end of a bell crank lever 55 pivoted on a pin 56 carried between ears 57 on the wringer head. The other end of the lever 55 is provided with a fork 58 receiving a pin 59 fixed in a latch member 60 loose on the shaft 50. The latch member 60 serves as an operating member for moving the slide 43. Upon movement of the slide 43 to its driving positions, the associated parts are moved to the positions illustrated respectively in Figs. 6 and 7, in which shoulders 61 of a latch member 62 co-operate with shoulders 63 on the latch member 60 to hold the driving mechanism in the respective operative positions. The latch member 62 is pivoted on the pin 56 and is urged by a spring 64 toward the latch member 60. It is necessary to latch the wringer driving mechanism in the operative position since otherwise the mechanism would be returned to the neutral position by the spring 44. The latch member 62 is made in two parts one of which, as has been already described, cooperates with the latch member 60 and the other of which cooperates with a latch releasing member 65 keyed to the shaft 50 and having a lost motion connection with the latch member 60 provided by a pin 66 in the latch member 60 and a slot 67 in the latch releasing member 65. The latch releasing member 65 has cam projections 68 which cooperate with the latch member 62 to lift it clear of the latch member 60 upon movement of the latch releasing member when the mechanism is in either of its driving positions. The latch releasing member also has a cam projection 69 intermediate the cam projections 68 which fits in a notch 70 in the latch member 62 when the mechanism is in the neutral position illustrated in Fig. 5.

Due to the lost motion connection between the latch releasing member 65 and the wringer driving mechanism, the initial turning movement of the control handles 49 merely moves the latch releasing member 65 to lift the latch member 62 clear of the latch member 60. If the driving mechanism is in either of the operative positions illustrated in Fig. 6 or 7, the release of the latch 62 permits the return of the driving mechanism to the neutral position by the biasing spring 44. If the driving mechanism is in the neutral position shown in Fig. 5, further turning of the handles 49 takes up the lost motion between the latch releasing member and the latch member 60 and causes movement of the driving mechanism toward one of its operative positions. Upon reaching the operative position the latch member 62 is moved by the spring 64 into engagement with the latch member 60 to hold the driving mechanism in the operative position.

The operation of the emergency release is controlled by a lever 71 pivoted on the stud 27 on the wringer head and carrying a roller 72 co-operating with inclined cam faces 73 fixed to an arm 74. One end of the arm 74 is pivotally connected to the emergency release operating link 25. The other end of the arm 74 is fixed to a shaft 75 pivoted in bosses 51 and 52. The lever 71 carries a pin 76 which fits in a groove 77 in the collar 54 which is fixed to the shaft 50. Upon axial movement of the shaft 50 in either direction from the position illustrated in Fig. 5, the roller 72 cooperates with one of the inclined cam faces 73 and moves the emergency release operating link 25 to the right, thereby pivoting the latch 21 clear of the pin 20 and releasing the pressure between the rolls. Upon operation of the emergency release, the top frame member 13 flies upward. The latch member 62 is provided with a tongue 78 which extends through an opening 79 in a plate 80 fixed to the top frame member. Upon upward movement of the top frame member due to operation of the emergency release, the plate 79 lifts the latch member 62 clear of the latch member 60 so that the wringer driving mechanism can be returned to the neutral position by the biasing spring 44. The cam faces 73 are held in engagement with the roller 72 by the spring 26. The inclined cam faces 73 act through the roller 72 and the pin 76 to center the shaft 50 in the position illustrated in Fig. 5 in which the stop pin 53 and the collar 54 are spaced substantially equal distances from the bosses 51 and 52. Because the shaft 50 is centered, the emergency release may be operated from either side of the wringer by pushing or pulling the handle 49 nearest the operator.

The safety of the wringer is increased by the fact that the operator uses a single handle to control the driving of the rolls and the operation of the emergency release.

In Figs. 8 to 13, inclusive, is shown a modification which differs from the previously described construction in the location of the control handles and the connections between the control handles and the driving mechanism and emergency release. In other respects the construction of the wringer is the same, and corresponding parts are indicated by the same reference characters.

The wringer is controlled by handles 81 fixed to opposite ends of a shaft 82 slidably and rotatably carried in bushings 83 in the side walls of the top frame member 13. The shaft is biased to

the central position illustrated in Fig. 10 by compression springs 84 arranged between the handles and the adjacent bushings. Pinned to the shaft 82 is a collar 85 having inclined faces 86 co-operating with inclined faces 87 on one end of the emergency release latch 21. The emergency release latch 21 is biased into engagement with the pin 20 by a tension spring 88. By pushing or pulling on either handle 81 the shaft 82 is moved axially and the inclined faces 86 cooperate with the inclined faces 87 to pivot the emergency release latch 21 to the releasing position. The operation of the emergency release is accordingly the same as in the previously described construction in that the operator merely pushes or pulls one of the handles.

The wringer is driven through reversing mechanism controlled by a clutch 89 which is moved up or down from the neutral position illustrated in Fig. 9 by a yoke 90 at the lower end of a slide 91. The slide 91 is biased to the neutral position by a compression spring 92 arranged between seats 93 on the wringer head. The ends of the spring 92 cooperate with shoulders 94 on the slide to bias the slide to the neutral position. The upper end of the slide 91 is provided with a notch 95 receiving one end 96 of a bell crank lever 97 pivoted at 98 on the wringer head. The other arm 99 of the bell crank lever has a latch member 100 pivoted thereon by a pin 101. The latch member 100 is pivotally connected by a pin 102 to a bar 103, one end of which is connected to an arm 104 keyed to the shaft 82 and the other end of which is slidably carried on the wringer head by means of a stud 105 on the wringer head extending through a slot 106 in the bar. The pivotal movement of the latch member 100 relative to the bar is limited by stops 107 on the bar. The bar 103 is shown in the neutral position in Fig. 8. Upon turning of the shaft 82 the arm 104 slides the bar 103 along the top of the wringer head. During the initial sliding movement of the bar 103, the pin 101 remains stationary and the latch member 100 pivots about the pin 101 until it engages one of the stops 107. Further movement of the bar causes movement of the bell crank lever 97 through the pin 101 connecting the latch member 100 and the bell crank lever. The stops 107 and the pivot pins 101 and 102 provide a lost motion connection between the bar 103 and the bell crank lever 97 which is equivalent in operation to the lost motion connection between the latch member 60 and the latch releasing member 65 in the previously described construction. Upon movement of the bar 103 to either of the operative positions shown in Figs. 11 and 12, one of the notches 108 on the latch member 100 cooperates with one of the teeth 109 on the wringer head to hold the mechanism in the operative position. Upon turning the handle 81 in the direction to move the bar 103 from one of the operative positions the initial movement of the bar causes the latch member 100 to pivot about the pin 101, moving the notch 108 clear of the teeth 109 with which it was in engagement. Upon releasing the latch 100 the biasing spring 92 returns the driving mechanism to the neutral position.

Upon operation of the emergency release in either of the driving positions, the top frame member 13 pivots upward about the bracket 15, lifting the bar 103 through the arm 104 and lifting the latch member 100 through the pin 102 to move the latch member clear of the teeth 109. This permits the return of the driving mechanism

to the neutral position under the force of the biasing spring 92.

What I claim as new and desire to secure by Letters Patent of the United States is:

- 5 1. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, and connections between the shaft and the driving mechanism operated by rotation of the shaft.
- 10 2. In a wringer, roll driving mechanism, a member for shifting the driving mechanism to operative and inoperative positions, a slide, a latch member pivoted on the slide, stops limiting the pivotal movement of the latch member relative to the slide, a connection between the latch member and the shifting member whereby the shifting member is moved by the latch member, and means engageable by the latch member to hold the shifting member in an operative position.
- 15 3. In a wringer, roll driving mechanism, a member for shifting the driving mechanism to operative and inoperative positions, a shaft, a handle for turning the shaft, an operating member loose on the shaft for moving the shifting member, a latch cooperating with said member to hold the shifting member in an operative position, a latch releasing member keyed to the shaft, and a connection between the handle and said operating member having sufficient lost motion so the latch releasing member is moved to the latch releasing position prior to the movement of the handle necessary to take up the slack between the handle and the operating member.
- 20 4. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved by rotation of said shaft, a connection between the latch releasing member and the shifting member effective upon movement of the handle to the latch releasing position to move the shifting member, and means responsive to operation of the emergency release for releasing the latch.
- 25 5. In a wringer, rolls, driving mechanism for the rolls, an emergency release for releasing the pressure between the rolls, a shaft mounted for movement along and for rotation about its axis, means for selectively rotating the shaft or moving the shaft axially, means responsive to axial movement of the shaft for operating the emergency release, a member for shifting the driving mechanism to operative and inoperative positions, a latch for holding said shifting member in an operative position, a latch releasing member moved in response to rotation of said shaft, a connection between the latch releasing member and the shifting member effective upon rotation of the shaft to the latch releasing position to move the shifting member, and means
- 30 6. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved by rotation of said shaft, a connection between the latch releasing member and the shifting member effective upon rotation of the shaft to the latch releasing position to move the shifting member, and means
- 35 7. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved by rotation of said shaft, a connection between the latch releasing member and the shifting member effective upon rotation of the shaft to the latch releasing position to move the shifting member, and means
- 40 8. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved by rotation of said shaft, a connection between the latch releasing member and the shifting member effective upon rotation of the shaft to the latch releasing position to move the shifting member, and means
- 45 9. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved by rotation of said shaft, a connection between the latch releasing member and the shifting member effective upon rotation of the shaft to the latch releasing position to move the shifting member, and means
- 50 10. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved by rotation of said shaft, a connection between the latch releasing member and the shifting member effective upon rotation of the shaft to the latch releasing position to move the shifting member, and means
- 55 11. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved by rotation of said shaft, a connection between the latch releasing member and the shifting member effective upon rotation of the shaft to the latch releasing position to move the shifting member, and means
- 60 12. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved by rotation of said shaft, a connection between the latch releasing member and the shifting member effective upon rotation of the shaft to the latch releasing position to move the shifting member, and means
- 65 13. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved by rotation of said shaft, a connection between the latch releasing member and the shifting member effective upon rotation of the shaft to the latch releasing position to move the shifting member, and means
- 70 14. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved in response to rotation of said shaft, a connection between the latch releasing member and the shifting member effective upon rotation of the shaft to the latch releasing position to move the shifting member, and means
- 75 15. In a wringer, rolls, driving mechanism for the rolls, an emergency release for releasing the pressure between the rolls, a shaft mounted for movement along and for rotation about its axis, a handle for selectively rotating the shaft and moving the shaft axially, a lever for operating the emergency release, a cam having a face co-operating with the lever to operate the emergency release upon axial movement of the shaft, a member for shifting the driving mechanism to operative and inoperative positions, a latch for holding said shifting member in an operative position, a latch releasing member moved in response to rotation of said shaft, a connection between the latch releasing member and the shifting member effective upon rotation of the shaft to the latch releasing position to move the shifting member, and means

responsive to operation of the emergency release for releasing the latch.

6. In a wringer, rolls, driving mechanism for the rolls, an emergency release for releasing the pressure between the rolls, a handle, means responsive to a thrust on the handle in a direction transverse to the rolls for operating the emergency release, and means responsive to movement of the handle in a direction parallel to the rolls for controlling the driving mechanism.

7. In a wringer, rolls, driving mechanism for the rolls, a shifting member for shifting the driving mechanism to operative and inoperative positions, an emergency release for releasing the pressure between the rolls, a shaft mounted for movement along and for rotation about its axis, a handle for selectively rotating the shaft and moving the shaft axially, operative connections between the shaft and the emergency release operated upon axial movement of the shaft, an operating member loose on the shaft and rotatable to move the shifting member, a latch co-operating with said member to hold the shifting member in an operative position, a latch releasing member keyed to the shaft, and a connection with the latch releasing member for rotating said operating member upon rotation of the latch releasing member, said connection having sufficient lost motion so the latch releasing member is moved to the latch releasing position prior to

rotation of the handle necessary to take up the slack between the latch releasing member and the operating member.

8. In a wringer, rolls, driving mechanism for the rolls, an emergency release for releasing the pressure between the rolls, a handle mounted for rotation about and movement along an axis, means responsive to axial movement of the handle for operating the emergency release, and means responsive to rotation of the handle for controlling the driving mechanism.

9. In a wringer, rolls, driving mechanism for the rolls, an emergency release for releasing the pressure between the rolls, a handle mounted for movement in a direction parallel to the rolls, means responsive to a thrust on the handle in a direction transverse to the rolls for operating the emergency release, a member for shifting the driving mechanism to operative and inoperative positions, a latch for holding said shifting member in an operative position, a latch releasing member moved in response to movement of the handle parallel to the rolls, a connection between the latch releasing member and the shifting member effective upon movement of the handle to the latch releasing position to move the shifting member, and means responsive to operation of the emergency release for releasing the latch.
